Primary Examiner—A. Hugo Word**Assistant Examiner**—Doris Clark**Attorney, Agent, or Firm**—Darby & Darby[57] **CLAIM**

The ornamental design for a ceramic tile unit for a floor or a wall, as shown and described.

DESCRIPTION

The FIGURE is a top plan view of a ceramic tile unit for a floor or a wall showing my new design, the rear being plain and unornamented.

The sides of the tile unit for a floor or a wall being of a conventional thickness.
